UNITED STATES PATENT OFFICE

154,672

DESIGN FOR A SPECTACLE FRAME

Beatrice Fornicoia, Rochester, N. Y.

Application February 26, 1948, Serial No. 144,760

Term of patent 14 years

(Cl. D57—1)

To all whom it may concern:

Be it known that I, Beatrice Fornicoia, a citizen of the United States, residing at Rochester, in the county of Monroe and State of New York, have invented a new, original, and ornamental Design for a Spectacle Frame, of which the following is a specification, reference being had to the accompanying drawing, forming part thereof.

Fig. 1 is a plan view;

Fig. 2 is a side elevational view of a spectacle frame, showing my new design; and

Figs. 3 and 4 are sectional views on the lines 3—3 and 4—4, respectively, of Fig. 2.

The essential features of my design reside in the temples shown in full lines and which increase gradually in width from the connection

with the front of the spectacle frame to the rounded portion at the free ends thereof, these free ends being bent slightly downwardly and being oval in cross section.

I claim:

The ornamental design for a spectacle frame, substantially as shown and described.

BEATRICE FORNICOIA.
